(57) **CLAIM**

The ornamental design for a media cutting device, as shown and described.

DESCRIPTION

FIG. 1 is a perspective view of a media cutting device according to the present invention;

FIG. 2 is a top plan view of the device illustrated in FIG. 1; FIG. 3 is a bottom plan view of the device illustrated in FIG. 1;

FIG. 4 is a left side view of the device illustrated in FIG. 1; FIG. 5 is a right side view of the device illustrated in FIG. 1;

FIG. 6 is a front view of the device illustrated in FIG. 1; and, FIG. 7 is a rear view of the device illustrated in FIG. 1.

The structure depicted by means of broken lines in the figures has been shown for illustrative purposes only and forms no part of the claimed design.
